UNITED STATES PATENT OFFICE

2,055,045

HAND OILER

Samuel O. Paull, Wellsburg, W. Va., assignor to
 Eagle Manufacturing Company, Wellsburg,
 W. Va., a corporation of West Virginia

Application November 19, 1935, Serial No. 50,572

5 Claims. (Cl. 221—51)

This invention is directed to an improvement in hand oilers of the type including a container, a delivery spout and a manually operable pumping mechanism to force the material from the container through the spout.

In hand oilers of this type, which are particularly designed to be held in one hand and operated by the fingers of that hand, it has been found that the container proper is frequently distorted and rendered ineffective, or at least objectionable, by reason of such distortion. Ordinarily, the container is constructed of relatively thin metal of smooth exterior and yields more or less readily even under the continued pressure of the hand in continued reuse of the oiler. The main source of distortion, however, is the rough usage to which oilers of this type are ordinarily subjected, being frequently dropped onto concrete flooring and not infrequently laid down on the floor after use and then stepped on accidentally, with the result that the oiler is either rendered incapable of proper use thereafter or is so distorted as to be difficult to hold and operate. Furthermore, where the exterior surface of the container is smooth, it is sometimes difficult to retain the grip on this surface and maintain the direction of the spout for the delivery of the oil in the desired direction, particularly when the part being oiled is somewhat difficult to reach.

Therefore, one of the principal objects of the present invention is to provide the wall of the container of corrugated form, both with a view of providing for a better grip during the use of the oiler and with a view to increasing the strength of such wall against that character of distortion to which a smooth wall would readily yield.

Again, in oilers of this type, at least generally speaking, some part of the mechanism, either the spout or a part of the pumping apparatus, is carried by and secured to the closing cap of the container, so that when this cap is removed to refill the container, as is of course frequently necessary in relatively small oilers of this type, the part of the mechanism which is carried by or secured to the cap is necessarily removed with the cap and as such part or parts are usually covered with oil or contain oil within them, there is a constant drip of such contained oil from these parts when the cap is removed for a refilling of the container.

A further object of the invention, therefore, is the provision of means by which the pumping apparatus to be manually operated and the connection leading to the spout are secured to the container and are wholly free of any connection with

the cap, with the result to avoid the objectionable dripping and contamination of oil over other surfaces when the cap with any attached parts is removed, as in previous conventional structures of this type.

Heretofore in oilers of this type, the operating parts are connected together and independently connected to the different parts of the container. For example, part of the pumping device will be connected to the container and the operating member therefor will be carried by the cap or exteriorly secured or mounted on the container. Therefore, when repair is necessary, there is considerable difficulty in removing all parts of the mechanism for replacement of parts or other correction.

Another object of the invention, therefore, is to provide all pumping elements and delivery parts within the container as a unit and fix such parts in proper relation in the container through the medium of a single connection, with the exterior parts, such as the spout and mechanical pump operator, arranged for threaded connection with the interior parts through the wall of the container. Thus, on the removal of the exterior parts and of the single interior connection, the entire structure may be readily removed as a unit for such repair or replacement operation as may be found necessary.

The invention is illustrated in the accompanying drawing, in which:

Figure 1 is a view in elevation of the improved hand oiler.

Figure 2 is a longitudinal section of the same, with the pumping parts in elevation.

Figure 3 is an enlarged vertical sectional view, partly in elevation, of the pumping unit.

The improved hand oiler includes a container having a diameter to be conveniently grasped in the hand and a length appropriate to the length of hand oilers of this type. The wall of the container has smooth upper and lower margins 2 and 3 intermediate which the full length of the wall is corrugated at 4 with the corrugations of sufficient curvature to more or less accommodate the fingers of the user. The container is permanently closed at the bottom, as at 5, with the upper margin 2 exteriorly threaded to receive a cap 6.

The pumping and delivery apparatus for the oil is made up as a unit including a fluid delivery channel 7 and an underlying vertically aligned pump cylinder 8. These elements are connected in vertical alignment and in axially parallel relation by a web 9 which at one end, termed the inner end, integrally supports a tube 10 which

extends at right angles to the channel 7 and cylinder 8 and is in open communication with each.

The tube 10 extends slightly above the fluid delivery channel at 11 and below the pump cylinder 8 at 12, and immediately above the communication between the tube 10 and the pump cylinder 8, the interior of the tube is formed with a valve seat 13. In the tube 10 below the pump cylinder, there is formed an interior rib 14 to slightly reduce the diameter of the tube to provide a limit abutment for a spring to be later described.

Threaded into the lower end of the tube 10 is a pipe section 15, the extreme upper end of which is formed as a valve seat 16 and which pipe section, somewhat below the tube 10, is deflected laterally, with its open inlet end 17 arranged adjacent the wall of the container and sufficiently close to the bottom to withdraw practically all of the fluid from the container in the pumping operation.

The length of the fluid delivery channel and pump cylinder, with the added diameter of the tube 10, is slightly less than the diameter of the container, and the entire unit so described is held in position and supported from an angle bracket 18 secured to the inner wall of the container adjacent the upper end, with the horizontal leg perforated to receive a set-screw 19 which threads into the upper extension 11 of the tube 10.

This screw 19 forms the sole supporting element of the pumping unit within the container, and when so connected, the tube 10 extends vertically of the container adjacent one side wall while the fluid channel 7 and pump cylinder 8 extend transversely of the container with their open ends remote from the tube 10 immediately adjacent and substantially in contact with the container wall.

The valves employed include a ball valve 20 which rests upon the valve seat 13 and opens under upward pressure in the tube 10 to establish communication between the tube or pump cylinder and the fluid channel 7. This ball valve is held normally closed by a light spring 21 which bears upon the valve and is held under appropriate tension by the free end of the set-screw 19. A second ball valve 22 is arranged to cooperate with the seat 16 at the upper end of the pipe section 15, this valve also opening upwardly and being held in normally closed position by a light spring 23 which bears between the valve 22 and the rib 14.

A hollow plunger 24 having a machine fit within the pump cylinder 8 is arranged in that cylinder, with the closed end of the plunger extending toward the open end of the cylinder, a spring 25 seated in the hollow plunger and bearing against the opposite wall of the tube 10 serving to maintain the plunger at its extreme outward limit of movement with respect to the cylinder 8.

A delivery spout 26 has a threaded terminal 27 designed to be passed through an opening 28 in the wall of the container in line with the open end of the delivery channel 7, with such threaded terminal engaging the interiorly threaded section of the channel at such open end. Adjacent the threaded end, the spout may be enlarged and formed to provide a section 29 for wrench application and removal of the spout. The free end of the spout, which of course may be of any length and preferably though not necessarily rigid, has a terminal nozzle 30 which may be formed for the delivery of the desired character of fluid.

The means for mechanically operating the pump plunger 24 is also mounted exteriorly of the container. This includes a rod 31 having a disk

head 32 of a size to fit within the pump cylinder 8 and engage and operate the hollow plunger 24 against the influence of the spring 25. This rod is passed through an opening 33 in the wall of the container, and a threaded nipple 34 freely slideable on the rod has a threaded terminal 35 which passes through the opening 33 and is threaded into the end of the pump cylinder 8. The opposite end of the nipple is threaded to receive a gland 36 to provide a non-leaking connection 10 between the rod and nipple. The free or outer end of the rod 32 is provided with an enlarged head 37 serving as a finger-piece for operating the rod.

It is to be particularly noted that all parts of the pumping apparatus are carried by the container and that not a single part of the operating mechanism is connected to or carried by the cap. Therefore, when it is necessary to refill the container, the removal of the cap does not necessitate corresponding removal of any of the interior parts which would necessarily be objectionable as they are covered with oil and would mar or drip on any surface on which the cap was laid during the refilling operation.

Of course, it is apparent that on inward movement of the plunger 24 through corresponding movement of the rod 31, air contained in the pump cylinder is forced past the valve 20 and out through the spout and that on release of the pressure on the rod 31, the return of the plunger 24 under the influence of the spring 25 will draw up into the tube 10 the fluid from the container. Of course, the valve 22 opens during this flow of the container incident to the atmospheric pressure 35 on the surface of the fluid beyond the pumping apparatus and at the same time the valve 20 is closed. After several movements of the plunger to prime the pump, that is fill the conduits, all succeeding movements of the plunger, as long as 40 fluid is within the container, draws such fluid into the pump cylinder on the outward movement of the plunger 24 under the influence of the spring 25 and forces such contained fluid past the valve 20 and out through the fluid delivery channel 7 and the spout.

The corrugated wall of the container is particularly important in hand oilers of this type. It permits the container to be made up of appropriate material of usual gauge while at the same 50 time providing an unusual strength to the otherwise unprotected wall of the container to avoid distortion of that wall under unusual pressure of the hand in the use of the oiler or any casual fall or contact of such container which would otherwise have the effect to mar and possibly seriously indent such container wall with corresponding objectionable appearance or, in exaggerated cases, complete disruption of the oiler.

Another important feature is the mounting of 60 the pumping apparatus by a single screw on the interior of the container and from the container wall, with all connected parts wholly free of any connection with the cap. Thus, when the spout and plunger operating rod are removed, which 65 may be readily and conveniently carried out from the exterior of the container, the removal of a single screw (19) and the slight turning of the pumping apparatus from beneath the bracket permits such apparatus to be removed as a whole 70 from the interior of the container.

The pump cylinder 8 has a vent opening 37 serving not only as a vent but acting also as an intake for the oil from the body of the cylinder in the initial stroke of the pump plunger to admit 75

sufficient oil to serve as an oil seal for the plunger. Furthermore, when the parts are inactive, the head 32 of the plunger rod 31 rests against the end of the threaded nipple 34 to seal this connection against leakage.

It is to be particularly noted that because the spout is directed from the side of the container body and the plunger operative by one finger of the hand grasping the container body, pump operation is permitted without tendency to divert the direction of the flow from the spout. In containers of this type as previously constructed, where the pump-operating element is connected to and arranged above the top of the container, the action on the lever for operating this element serves to divert the spout from the direct line intended and thus fail to deliver the oil at the exact spot desired with consequent wastage. The present construction entirely obviates this as the action of the plunger is in direct line with the grip and has no tendency to twist or turn the container under the pump action. Thus, the spout may be directed to the exact point desired to be lubricated and held at that point without variation during the pumping operation.

What is claimed to be new is:

1. A hand oiler including a container, a cap closing one end thereof, a pumping mechanism arranged in the container, said pumping mechanism including a fluid delivery channel, a pump cylinder, and an intercommunicating tube formed as a unit, a bracket secured to the interior of the container, and a set-screw leading through the bracket and removably connected to the tube for supporting the unit within the container.

2. A hand oiler including a container, a cap closing one end of the container, a pumping mechanism within the container and, said pumping mechanism comprising a unitary structure including a tube arranged longitudinally of the

container, a pump cylinder extending laterally of and in communication with the tube, and a fluid delivery conduit extending laterally of and in communication with the tube, and a single element engaging the cylinder and engaging and closing the end of the tube above the delivery conduit.

3. A construction as defined in claim 2, where-in the container is formed with openings to register with the free end of the delivery conduit and with the free end of the pump cylinder, a delivery spout projecting outwardly of the wall of the container and extending through the opening in line with the delivery conduit for connection with said conduit, and pump operating means extending through the opening in the wall of the container in line with the pump cylinder.

4. A hand oiler including a container of substantially uniform diameter throughout having a corrugated wall and an upper open end substantially of the full diameter of the container, a removable cap closing said end, a pumping unit including a tube arranged longitudinally of the container, a fluid delivery conduit, and a pump cylinder extending laterally from and in communication with the tube, means extending through the wall of the container and removably connected to the fluid delivery conduit for fluid delivery purposes, means extending through the wall of the container and adapted for removable connection with the end of the pump cylinder for pumping purposes, and an element fixedly and removably connecting the tube and container immediately below the cap.

5. A construction as defined in claim 4, where-in the element includes a set-screw cooperating with a fixed projection of the container and threaded into the tube above the fluid delivery conduit.
